UNITED STATES PATENT OFFICE

156,585

LENS FOR STOP AND TURN SIGNALS

Homer J. Vetter, Seattle, Wash.

Application August 30, 1948, Serial No. 148,375

Term of patent 14 years

(Cl. D72—1)

To all whom it may concern:

Be it known that I, Homer J. Vetter, a citizen of the United States, and a resident of Seattle, in the county of King and State of Washington, have invented a new, original, and ornamental Design for a Lens for Stop and Turn Signals, of which the following is a specification, reference being had to the accompanying drawing, forming a part thereof.

Said drawing shows:

The single drawing figure is a front elevational view of a lens for stop and turn signals, showing my new design.

The nature of the design is substantially thin and flat.

I claim:

The ornamental design for a lens for stop and turn signals, as shown and described.

HOMER J. VETTER.
